UNITED STATES PATENT OFFICE.

JOSEPH DAIN, OF MOLINE, ILLINOIS, ASSIGNOR TO DEERE AND COMPANY, OF MOLINE, ILLINOIS.

VARIABLE-SPEED-TRANSMISSION MECHANISM.

1,413,217.

Specification of Letters Patent. Patented Apr. 18, 1922.

Application filed December 9, 1915, Serial No. 65,911. Renewed February 7, 1919. Serial No. 275,675.

To all whom it may concern:

Be it known that I, JOSEPH DAIN, a citizen of the United States, residing at Moline, in the county of Rock Island, State of Illinois, have invented certain new and useful 5 Improvements in Variable-Speed-Transmission Mechanism, of which the following is a specification, reference being had to the accompanying drawing.

This invention relates to variable speed transmission mechanism, being especially designed for securing a simple, strong, efficient power transmission mechanism suitable for tractors and capable of being produced at a comparatively low cost. One of the objects of my invention is to produce a compact variable speed mechanism capable of being used for this purpose so arranged and constructed as to occupy a minimum amount 20 of space and as to be capable of being assembled ready for use, and of being used continuously, without the necessity for delicate or difficult adjustments. Another object of 25 my invention is to provide a mechanism of this type which can be easily manipulated and controlled and which can be very quickly shifted from one speed to another. Further objects of my invention are to provide improved mechanism for changing from one 30 set of transmission gears to another set without shifting the position of any one gear relatively to its cooperating gear; to provide a new and improved construction and arrangement of parts by which the operator is 35 positively prevented from throwing into operation more than one set of driving elements at any one time, thus preventing the injury to the mechanism which might otherwise occur by reason of improper manipulation of the mechanism, and to improve 40 transmission mechanism in sundry details hereinafter pointed out. The preferred means by which I have accomplished my several objects is illustrated in the accompanying drawing and is hereinafter specifically described. That which I believe to be 45 new is set forth in the claims.

The drawing is substantially a horizontal cross-section through the preferred form of 50 my transmission mechanism as applied to a tractor, certain parts being in elevation.

In the drawing, 10 indicates a frame having connected to it at its forward end a motor 11 which may be of any suitable type, 55 in the construction shown being in the form

of an internal combustion engine. A circular drum 12 is fixedly connected in concentric position upon a plate 13 driven by the motor 11, which drum serves as an external clutch member, as hereinafter described. In the preferred embodiment of my invention as applied to a traction engine, the frame 10 serves as a connecting means between the motor and the transmission mechanism as hereinafter described; it 60 will be understood, however, that I do not wish to be restricted, except as hereinafter specifically claimed, to the use of a motor carried by or in close proximity to the frame 10, it being sufficient, broadly speaking, that 65 the drum 12 shall be driven from a suitable source of power, and for the purposes of this case said drum and the power mechanism by which it is rotated may be termed a "prime mover."

14 indicates a shaft mounted in concentric position relatively to the drum 12, being supported at its forward end by an anti-friction bearing 15 carried by the drum 12, and being supported at its rear end by an 70 anti-friction bearing 16 mounted upon the framework 10. The anti-friction bearing 16 bears at one side against a shoulder cut in the shaft 14 and is held against movement longitudinally of the shaft in the opposite 75 direction by means of a nut 17 secured upon the rear end of the shaft. The anti-friction bearing 16 thus serves to receive both the lateral pressure and the end thrust of the shaft 14. 18 indicates a collar fixedly 80 mounted upon the shaft 14 at an intermediate point therealong. Slidably mounted upon the forward end of the shaft 14 is a sleeve 19 which is caused by feathers 20 to rotate with the shaft 14. Links 21-22 are 85 pivotally mounted at their inner ends upon the sleeve 19 and are pivotally connected at their outer ends with an internal clutch member comprising friction blocks or shoes 23-24, respectively. As will be seen from 90 the showing in solid lines in the drawing, when the sleeve 19 is moved to its rearmost position so as to cause the links 21 to extend outward approximately at right angles to the shaft 14, the shoes 23-24 are brought 95 into frictional engagement with a suitable friction driving surface provided on the interior of the drum 12, thus causing the shaft 14 to rotate with the drum 12 and serving to drive the bevel pinion 25 which in the 100

105 construction shown is carried by the frame 10 and serves to drive the bevel pinion 26 which in the 110

construction shown is integral with the shaft 14. When, however, the sleeve 19 is moved to its forward position upon the shaft 14, as indicated in dotted lines, the friction shoes 23-24 are withdrawn out of contact with the drum whereby the drum is permitted to rotate independently of the shaft 14.

Revolutely mounted upon the shaft 14 between the bevel pinion 25 and the collar 18 10 is a sleeve 26. Slidably mounted upon the sleeve 26 is a second sleeve 27 which is caused to rotate with the sleeve 26 by the use of feathers 28. Links 29-30 are pivotally connected at their inner ends with the sleeve 15 27 and are pivotally connected at their outer ends with an internal clutch member comprising friction blocks or shoes 31-32 respectively. As shown in dotted lines in the drawing, when the sleeve 27 is in its 20 forward position the shoes 31-32 are held in operative frictional engagement with a suitable friction surface provided on the inner face of the drum 12 so as to cause the sleeve 27 and the sleeve 26 to rotate with the drum 25 12, serving thus to drive a bevel pinion 33 which in the construction shown is formed integrally with the sleeve 26. When, however, the sleeve 27 is in its rearmost position as shown in solid lines, the shoes 31-32 are 30 held out of operative engagement with the drum 12 and the drum is permitted to rotate independently of the sleeve 26 and the bevel pinion 33.

It will be noted that movement of the 35 sleeves 19 and 27 in the same direction reversely operates the shoes 23 and 31, respectively, and in order to prevent the operative connection of the shaft 14 and the sleeve 26 at the same time with the drum 12, the slid- 40 ably mounted sleeves 19 and 27 are connected together by means of links 34-35. The links 34-35 are pivotally connected at their rear ends with the sleeve 27 upon the same axis as that upon which the links 45 29-30 are pivotally mounted. The forward ends of the links 34-35 are connected with the sleeve 19 by means of a two-part band or collar 36 which is revolutely mounted in a suitable circumferential groove in the 50 sleeve 19. The sleeves 19 and 27 are shifted longitudinally of the shaft 14 by means of a lever 37 pivotally mounted upon the frame 10 connected at its free end with a two-part band or collar 38 revolutely mounted in a circumferential groove in the collar 27. The lever 37 is provided with a suit- 55 able hand-latch 39 of any suitable type adapted to engage a rack 40, whereby the sleeves 19-27 may be held in their rearmost 60 position to drive the shaft 14, or in their forward position, so as to drive the sleeve 26, or in an intermediate position, in which case both sets of friction shoes are freed from engagement with the drum 12.

65 From a careful consideration of the above

description in connection with the drawing it will be seen that either the pinion 25 or the pinion 33 can be driven by power from the drum 12 as desired, the operator being enabled by the use of the lever 37 to shift the 70 two internal clutch members easily and almost instantaneously so as to drive either through the set of driving elements comprising the pinion 25 or through the other set of driving elements comprising the pinion 33 75 and as said pinions and the devices through which they are respectively connected with the drum 12 are concentric with the axis of said drum, the power is transmitted directly from the prime mover to said pinions, thereby avoiding loss of power and other objections incident to the use of the intermediate gearing, or other connections, necessary where straight line transmission can not be employed. My improved construction also 80 makes it practicable to employ cooperating friction clutch members of relatively great diameter as compared with the diameter of the pinions 25 and 33, so that great driving torque is obtained, and the coacting clutch 85 members are not subjected to undue strain.

The means for transmitting power from the pinions 25-33 comprises, in the embodiment of my invention illustrated, a transversely-extending shaft 41 mounted in suitable bearings 42-43 upon the frame 10 at right angles to the shaft 14. Gears 44-45 are mounted on a common axis, i. e., with their axes alined, in the construction shown said gears being revolutely mounted upon the 100 shaft 41 so as to mesh with the bevel pinion 33 at opposite sides thereof. The gear 45 is also provided with an annular gear 46 which meshes with the bevel pinion 25. As will be readily understood, when power is applied 105 from the drum 12 through the sleeve 26 to the bevel pinion 33, the gears 44 and 45 will be rotated by the pinion 33 in opposite directions about the shaft 41, the engagement of the gear 46 with the pinion 25 causing the 110 shaft 14 to run idly. Upon the shifting of the power from the pinion 33 to the pinion 25 by the proper manipulation of the lever 37 as above described, the gear 45 will be driven at a comparatively higher speed of 115 rotation, the higher speed being attained by reason of the fact that the gear 46 through which the power is then applied is of a smaller diameter than that of the gear 45. When power is applied thus through the 120 pinion 25 to the gear 46, the gear 44 is also driven at the same speed but in the opposite direction by reason of being effectively connected with the gear 46 through the gear 45 and the intermeshing pinion 33.

The means shown for applying power from the gears 44-45-46 comprises a driven member in the form of a heavy gear 47 mounted upon the shaft 41 and adapted to be moved freely longitudinally thereof. 125

Clutch members 48-49 are provided at opposite ends of the hub of the gear 47 adapted to engage respectively with suitable clutch members 50-51 carried by the gears 44-45. 5 With the gear 47 in the position shown in the drawing, the gears 44-45 are adapted to rotate without affecting the gear 47. Upon the movement of the clutch member 49 into engagement with the clutch member 51, the 10 gear 47 will be driven with the gear 45 at either its high speed movement or its low speed movement according to the position of the lever 37, as above described. Upon the movement of the clutch member 48 into engagement with the clutch member 50, the gear 47 will be driven in the opposite direction at either the high speed or the low speed rate of rotation, depending upon the 15 position of the lever 37.

20 The means provided for shifting the gear 47 and its clutch members 48-49 independently of the shaft 41 comprises a bifurcated arm 52, the forward ends of the arms of which engage suitable circumferential 25 grooves in the hub of the gear 47. The arm 52 is revolubly mounted at its rear end upon a rock shaft 53, but is held against longitudinal movement relatively to the rock-shaft 53. A lug 54 carried by the rock-shaft 53 is 30 adapted to engage any one of a plurality of notches of a rack 55 carried by the frame 10. Whenever it is desired to shift the gear 47 longitudinally of the shaft 41, the rock-shaft 53 is turned to carry the lug 54 out of engagement with the rack 55, whereupon the rock-shaft 53 can be moved longitudinally of itself to bring the gear 47 into the desired 35 clutching engagement. The rock-shaft 53 can then be turned into position to bring the 40 lug 54 into engagement with the rack 55 for holding the rock-shaft 53 and the gear 47 in the desired adjusted position. In the construction shown, the gear 47 is in mesh with a large gear 56 suitably mounted upon the 45 framework.

So far as I am aware, I am the first in the art to transmit power from a prime mover to a driven member by transmission mechanism comprising speed changing gearing,— 50 such as a plurality of gears of different diameter, or a gear having a plurality of series of concentric teeth,—and pinions constantly in mesh with said gearing, combined with means concentric with the axis of the prime 55 mover, for separately connecting either of said pinions directly with the prime mover and disconnecting the other therefrom practically instantaneously and without gear shifting; also to provide for effecting speed 60 changes, through such transmission mechanism by the operation of a single lever. I also believe myself to be the first to provide such a transmission mechanism with means for driving the driven member either in a 65 forward or in a reverse direction.

What I claim as my invention and desire to secure by Letters Patent, is—

1. A variable speed mechanism comprising a plurality of concentric gears of different diameter, pinions constantly in mesh with said gears respectively, a prime mover having a plurality of friction clutch surfaces, unidirectional independently rotating friction clutch members connected respectively with said pinions and adapted to be 75 alternatively connected with the prime mover, and unitary control means operatively connecting said independently rotating friction clutch members and adapted to be operated to connect the same alternatively 80 with the prime mover.

2. A transmission mechanism comprising two concentric gears of different diameter, two pinions constantly in mesh with said gears respectively, a driven friction clutch member for each of said pinions and rotatable independently of each other, a driving friction clutch member adapted to cooperate with either of said driven clutch members to drive the same, and means connecting said 85 driven clutch members and adapted to be operated to connect either of them with said driving clutch member and simultaneously to disconnect the other therefrom.

3. A transmission mechanism comprising 95 two concentric gears of different diameter, two pinions constantly in mesh with said gears respectively, a driven friction clutch member for each of said pinions and rotatable independently of each other, a driving 100 friction clutch member adapted to cooperate with either of said driven clutch members to drive the same, and a unitary operating device operatively connected with both said driven clutch members and adapted to be 105 operated to move either of said driven clutch members into operative engagement with said driving clutch member, and simultaneously move the other driven clutch member out of engagement therewith.

4. A transmission mechanism comprising 110 a driving friction clutch member, two independently rotatable driven clutch members adapted to be moved into or out of operative engagement with said driving clutch member, means connecting said driven clutch members and adapted to be operated to engage one of said driven clutch members with said driving clutch member and substantially coincidently disengage the other therefrom, pinions constantly having driving connection with said driven clutch members respectively, and concentric gears of different diameter constantly meshing with said pinions respectively.

5. A transmission mechanism comprising 115 two concentric gears of different diameter, two pinions constantly in mesh with said gears respectively, a shaft connected with one of said pinions, a sleeve loosely mounted 120

on said shaft and connected with the other pinion, two expanding friction clutch members mounted to rotate respectively with said shaft and sleeve, a driving friction clutch member adapted to cooperate with said expanding clutch members, an operating lever, and oppositely acting devices actuated by said lever for alternatively moving either of said expanding clutch members into or out of operative engagement with said driving clutch member.

6. A transmission mechanism comprising two oppositely-disposed rotary gears adapted to rotate about a common axis, one of said gears having a plurality of concentric series of teeth, a plurality of pinions meshing respectively with the different series of teeth of the latter gear, one of said pinions also meshing with the teeth of the other gear, a prime mover comprising a friction clutch member, friction clutch members permanently connected respectively with said pinions and adapted to cooperate with said first-mentioned clutch member, a lever for operating said friction clutch member to connect either of said pinions with the prime mover, and a driven member comprising a gear mounted concentrically with said first-mentioned gears and arranged to be operatively connected with either thereof.

7. A transmission mechanism comprising oppositely-disposed rotary members adapted to rotate about a common axis, a driven member mounted concentrically with said rotary members, and arranged to be separately connected with either of said rotary members, a prime mover, mechanism including a plurality of friction clutch devices associated with said prime mover and operating through said rotary members for rotating said driven member in either direction at a plurality of speeds without varying the speed or direction of the prime mover and unitarily operable means for simultaneously

operating said clutch devices reversely with relation to each other.

8. The combination of a shaft, two gears revolubly mounted thereon, a pinion between said two gears and meshing with both of them for driving them in opposite directions, a driven member mounted upon said shaft between said two gears, clutching mechanisms for connecting said driven member with either of said two gears, a bifurcated arm engaging suitable circumferential grooves in said driven member, a rock-shaft upon which said arm is revolubly mounted, means for holding said arm against movement longitudinally of said rock-shaft, a lug carried by said rock-shaft, and a rack adapted to engage said lug for holding the rock-shaft and the said driven member against movement longitudinally of said first-named shaft, said lug being adapted by a suitable rocking of the rock-shaft to be freed from said rack for an adjustment of said driven member.

9. The combination of a frame, a prime mover revolubly mounted on said frame, a drum secured to said prime mover and adapted to be rotated thereby in concentric position relatively to the axis of rotation of said prime mover, a shaft having one end revolubly mounted in said drum upon its axis of rotation, a friction clutch mounted on said shaft serving when in operation to brace said drum relatively to said shaft, a bevel pinion revoluble with said shaft, a bevel gear meshing with said bevel pinion tending to thrust said shaft when in operation longitudinally toward said drum, and an anti-friction bearing on said frame for said shaft serving to hold the shaft in alignment with the normal axis of rotation of the drum and to hold the shaft against movement longitudinally of itself.

JOSEPH DAIN.

Certificate of Correction.

It is hereby certified that in Letters Patent No. 1,413,217, granted April 18, 1922, upon the application of Joseph Dain, of Moline, Illinois, for an improvement in "Variable-Speed-Transmission Mechanism," an error appears in the printed specification requiring correction as follows: Page 4, line 25, claim 6, for the word "member" read *members*; and that the said Letters Patent should be read with this correction therein that the same may conform to the record of the case in the Patent Office.

Signed and sealed this 16th day of May, A. D., 1922.

[SEAL.]

KARL FENNING,

Acting Commissioner of Patents.
